Manufacturing Company, Elizabeth, N.J., a corporation of New Jersey

Filed May 26, 1959, Ser. No. 56,077

Term of patent 14 years

(Cl. D9—2)

Fig. 1.

Fig. 2

Fig. 1 is a perspective view of a workshop dust collector or similar article, showing my new design.

Fig. 2 is a slightly enlarged cross-sectional view taken on the line 2—2 of Fig. 1.

The opposite side of the workshop dust collector is substantially the same in appearance as the side disclosed in the drawing.

The essential features of my design reside in the portions shown in full lines in the drawing.

I claim:

The ornamental design for a workshop dust collector or similar article, as shown and described.
